(57) **CLAIM**

The ornamental design for a device for cavitation peeling of skin of head and facial hair as shown and described.

DESCRIPTION

FIG. 1 is a front elevation view of a device for cavitation peeling of skin of head and facial hair showing our new design; a rear side elevation view is a mirror image of the front elevation view;

FIG. 2 is a right side elevation view thereof; a left side elevation view is a mirror image of the right side elevation view thereof;

FIG. 3 is a top plan view thereof;

FIG. 4 is a top, front, left side perspective view thereof;

FIG. 5 is a bottom, front, right side perspective view thereof; FIG. 6 is a front elevation view of a second embodiment of the device for cavitation peeling of skin of head and facial hair showing our new design; a rear side elevation view is a mirror image of the front elevation view;

FIG. 7 is a right side elevation view thereof; a left side elevation view is a mirror image of the right side view thereof;

FIG. 8 is a top plan view thereof;

FIG. 9 is a top, front, left side perspective view thereof; FIG. 10 is a bottom, front, right side perspective view thereof;

FIG. 11 is a front elevation view of a third embodiment of the device for cavitation peeling of skin of head and facial hair showing our new design; a rear side elevation view is a mirror image of the front elevation view;

FIG. 12 is a right side elevation view thereof; a left side elevation view is a mirror image of the right side elevation view thereof;

FIG. 13 is a top plan view thereof;

FIG. 14 is a top, front, left side perspective view thereof; and,

FIG. 15 is a bottom, front, right side perspective view thereof.

The broken line showing of a handle is for the purpose of illustrating environmental structure and forms no part of the claimed design.
